FREDERICK J. H. HAZARD, OF TORONTO, ONTARIO, CANADA.

CABLE-CARRIER SYSTEM.

1,124,431.

Specification of Letters Patent.

Patented Jan. 12, 1915.

Application filed April 23, 1912. Serial No. 692,658.

To all whom it may concern:

Be it known that I, FREDERICK J. H. HAZARD, of the city of Toronto, in the Province of Ontario, Canada, have invented certain new and useful Improvements in Cable-Carrier Systems, of which the following is a specification.

This invention relates to cash carrier systems in which a box, suitably guided on tracks, is drawn by an endless cable from station to station, and my object is to devise a simple and efficient system of this type in which the outgoing and return tracks are arranged side by side, in which reliable automatic mechanism is embodied for engaging the boxes with the cable at all despatching stations and for disengaging them at receiving stations, in which selective automatic means are employed for discharging each carrier on the outgoing track at its own station and in which effective means are provided to prevent the cables jumping the guide pulleys at turns.

With this object in view my invention consists essentially of the constructions herein specifically set forth and particularly claimed.

Figure 1 is a side elevation of the cashier end of the system. Fig. 2 is a plan view of the same. Fig. 3 is a side elevation of an intermediate station showing the sending part and portion of the receiving part. Fig. 4 is a plan view of the same parts. Fig. 5 is a side elevation of a portion of the receiving part of an intermediate station shown in continuation of Fig. 3. Fig. 6 is a plan view of the same parts. Fig. 7 is a side elevation of a modification of the intermediate receiving station. Fig. 8 is a plan view of part of the same. Fig. 9 is a side elevation partly in section showing a corner of the system. Fig. 10 is a plan view of the same parts. Fig. 11 is an enlarged sectional detail showing the cable catching device formed by one of the rails and one of the grooved pulleys. Fig. 12 is a front elevation of the left hand supporting bracket shown in Figs. 9 and 10. Fig. 13 is a similar view of the next adjacent bracket toward the right. Fig. 14 is a side elevation partly in section of one of the boxes. Fig. 15 is an end view of the box. Fig. 16 is an enlarged end view of part of the cable gripping mechanism of the box.

In the drawings like numerals of refer-

ence indicate corresponding parts in the different figures.

In my system I employ two tracks each formed of two rails 1 preferably formed of round steel rod. These tracks are supported on brackets 2 each preferably formed of a closed frame-work and three vertical members 3. These members are provided with lugs 4 to which the rails are secured by screws or rivets 5. The lugs, it will be noted particularly on reference to Figs. 3 and 4, project lengthwise of the track, so that the rivets are easily got at from each side for riveting. One track, it will be noted, is slightly offset relative to the other, so that it stands at a different level. This makes no difference in the operation of the system, but enables me to get at the inner lugs 4 so that the rivets may be properly riveted, which could not be done if the tracks were in line.

6 represents the cables. These are carried and driven in ordinary manner and no description thereof is necessary. I show, however, at the cashier's end (see Fig. 1) the guide pulleys 7 and 8 over which the cables are led to the operating mechanism. I also show two corner guide pulleys 9 and 10 to which further reference will be made hereinafter. (See Fig. 10.)

Referring particularly to Figs. 1 and 2 which illustrate the cashier's end of the system, it will be seen that the outgoing track is bent down at the end and has its rails secured to a guide bracket 11 which is suitably shaped to serve as a guide for the box 12 when the latter is being pushed into position. This box is provided with the plate 13 fiber lined and having its under side secured to the top of the box intermediate its edges and adapted to rest on top of the rails 1 of the tracks. Anti-friction rollers 14 are journaled on the central line of the box, one toward each end to fit between the rails of the tracks to keep the box in line. (See Figs. 14 and 15.) When the box is slipped in place over the guide bracket 11 the ends of the rail 1 of the outgoing track fit under the plate 13. The cable 6 of the outgoing track, it will be noted, is led down to a position just above the end of the track. Each box is provided with cable gripping mechanism, which must be engaged with the cable as soon as the box is in proper position to run on the track. This cable gripping

mechanism is best seen in Figs. 14 to 16 of the drawings. The jaws 15 are provided both preferably movable and pivoted on the screws 16 screwed into the upturned end of the plate 13. These jaws are so shaped that, when in the position shown in Fig. 16 in dotted lines, they are in a position to receive a cable between them and when in the position shown in full lines 10 in Figs. 15 and 16, to firmly grip the same. These jaws are operated by means of a plunger 17 vertically movable in the guides 18 formed on or secured to the end of the box. This plunger is widened at its upper 15 end sufficiently to enable the slots 19 to be formed therein and these slots are adapted to engage pins 20 secured to the jaws 15. It is evident that by vertically reciprocating the plunger that the desired movements 20 may be imparted to the jaws 15. A coil spring 21 engages one of the guides 18, and a seat 22, formed in the lower portion of the plunger, which spring tends to move the plunger downward, and consequently the 25 jaws, to the cable gripping position. The yoke 23 is secured in position by means of the screws 16 and serves to hold up the cable in the proper position to be engaged between the curved faces 24 of the jaws 15. 30 The plunger 17, it will be noted, projects below the bottom of the box when the jaws 15 are in their cable gripping position. It will also be noted that an inclined cam surface 25 is rigidly supported from the out- 35 going track adjacent the guide frame 11. The inclination of this cam surface 25 is such that as the box is pushed on the track it gradually pushes up the plunger 17 so that the cable 6 will be received between the 40 jaws 15. The cable is gradually pushed up as the box advances so that it lies closely between the jaws. When the plunger reaches the end of the inclined cam surface 25 it is forced by the spring 21 to the cable 45 gripping position. The box is then drawn by the cable along the track until a discharge station is reached. This, if it is at the end of a line, will be very similar to the discharge station at the cashier's end, shown 50 in Figs. 1 and 2, with immaterial mechanical variations. It will be seen that near the end of the incoming track the cam surface 26, similar to the cam surface 25 but in a reverse direction, is supported below the 55 track so that when a car reaches this cam surface 26 its cable gripping mechanism is operated to release the cable. As at this point the cable tends to lift away from the box owing to the location of the guide pul- 60 ley 8, the cable is pulled clear of the jaws 15 by the time the plunger 17 has reached the end of the cam surface and the spring 21 again closes the jaws. The box then runs by its own momentum to the end of the in- 65 going track, where it passes off on to the

receiving chute 27 which is provided at the end with the elastic buffer 28.

At intermediate stations I preferably employ the arrangements shown in Figs. 3 and 4 of the drawings. Here the supporting brackets 2 for the tracks are adapted for connection with the brace rods 29 which are required to maintain continuity of connection between the parts of the ingoing track in which a gap is formed sufficient for the 75 plate 13 of a box to pass through. The gap is normally filled by the track section 30 which is formed of two rails suitably supported by the swinging frame 31. This frame is pivoted at 32 on a bracket 2 for 80 ward of the gap. The rearward end of the swinging frame is provided with curved members 33 to which the track section 30 is connected. These curved members also carry the track section 34 which when the 85 frame is swung up may be brought into the gap in the track to take the place of the track section 30. When the swinging frame is up it is evident that the box 12 will be in proper position to move forward on to the main track. Below the track section 34 an inclined cam surface 35 is suitably supported by the curved members 33. This cam surface 35 is suitably positioned so that the cable gripping mechanism of the 90 box is moved to its cable receiving position as the box is placed in position on the track section 34. An elastic buffer 36 is secured to the bracket 2 in the position shown to prevent the box being pushed too far forward when placed in position on the track section 34. I prefer to provide automatic means to push forward the box, when the track section 34 has been brought into the gap in the main track, so as to bring the 100 box to a position in which the plunger passes off the end of the cam surface 35 and permits the cable gripping mechanism to move to its cable gripping position. For this purpose I provide the cam lever 37 pivoted 105 on the bracket 2 at the rear side of the gap in the track. This cam lever is so pivoted and bent that it may be rocked to engage the rear end of the box when the track section 34 is nearly in position to span the gap 110 in the track. The lever is provided with the finger 38 adapted to be engaged by the plate 13 of the box. By the time the track section 34 is in proper position in the gap 115 in the main track the finger 38 has been 120 rocked sufficiently to cause the lever 37 to push the box forward as desired, and the cable gripping mechanism of the box to engage the cable, which forthwith draws away the box. 125

At intermediate discharge stations it is important that only that particular box be discharged which is appropriate to that station. For this reason selective discharge mechanism must be employed. It will be noted, 130

particularly on reference to Figs. 5 and 6 that a gap is formed in the outgoing track. The brackets 2 at opposite sides of the gap may have secured thereto the brace rods 29 which maintain continuity of connection past the gap in the track. (See Fig. 7.) Below each rail at each side of the gap I provide a support 40. These supports are adapted to receive the thin bars 41. For 10 this purpose slots are formed in the supports in which the bars may be fitted and held in place by the pins 42. The lowermost bar 41 forms a Y with the thin bar 43 which is curved down to a lower level and is engaged with the lower support 44 similar to the upper supports 40 and in which the curved bar 43 may be secured in any one of a plurality of positions. Paralleling the bar 43 is a second curved bar 45 connected 20 with one of the supports 40 and with the lower support 44. Of course a pair of these curved bars 43 and 45 is employed beneath each rail of the track.

The boxes it will be noted particularly 25 on reference to Figs. 14 and 15 are provided at opposite sides with pairs of lugs 46. These are preferably formed of L-shaped pieces having part riveted to the box inside the same and part projecting through a 30 slot in the side of the box. Each box is preferably provided with a plurality of slots, so that the lugs may be secured to the box in any desired position. Each box will have the lugs secured to it in a different 35 vertical plane. The box which is designed to pass out at an intermediate station nearest the cashier's end will have the lugs in the lowest position, and the box intended to pass out near the end of the line will have 40 its lugs in the highest position. Each intermediate station will have the curved bars 43 and 45 secured to the supports 40 and 44 in a suitable position to enable the lugs 46 of the appropriate box to pass between these 45 bars, so that the box will be guided down below the track while a sufficient number of straight bars 41 will be employed to guide the other boxes by means of the lugs 46 over the gap, each box riding on the bars 50 appropriate to the position of its lugs. As the supports will be the same at all of the stations, it is merely necessary to employ at any given station the proper number of straight bars and to locate the curved bars 55 in the proper position to engage the lugs of the proper box for that station.

When a box has been carried down to a lower level, as described, it is necessary to release it from the cable and to guide it to 60 a convenient position to be received by the salesman. I, therefore, provide at the lower level the track 47 preferably supported with brackets 2 at the forward side of the gap in the track and bent around in a half circle 65 to discharge beneath the adjacent ingoing

track, as shown particularly in Figs. 4 and 5. Where the box which has been drawn down enters on the track 47, I suitably support below the track the inclined cam surface 48 which is suitably shaped to force 70 up the plunger 17 of the box and release the cable gripping mechanism. The cable being carried well above the track 47 pulls out of the jaws 15 as soon as the latter opens so that the box is free to run around the 75 track and shoot off the other end thereof.

A modification of the intermediate discharge station is shown in Figs. 7 and 8. In this construction, instead of employing straight bars 41 I span the gaps in the 30 tracks by pivoted sections 49. These have their ends bent around to form the pivots 50 which have a bearing in the bracket 2 at the end of the gap. Coil springs 51 wound on the pivots 50 and suitably engaging 35 these pivots and the bracket tend to hold the pivoted sections 49 in the position shown in the drawings, the tension of the spring being sufficient to enable the pivoted sections to carry a box across the gap. 90 The straight bars being dispensed with, the support 40 is needed below each rail merely at the end of the gap adjacent the pivots 50. I prefer, however, to employ three lower supports 44 and to lengthen the 95 curved bars 43 and 45, as shown in Fig. 7. The operation of this modification is much the same as that previously described, the curved bars being suitably set to engage the lugs 46 of the box appropriate to a 100 given station. I show, however, a slight variation of the cable release mechanism. The curved bars 43 and 45 in turning down gradually approach the horizontal again, so that a substantially horizontal surface 52 105 will be employed instead of the inclined cam surface 48. Below the gap in the track I prefer in this modification to somewhat separate the curved bars and to space them 110 from one another by means of a spacer 53 suitably riveted in place toward the outer sides of the bars. I find that as the car retains connection with the pivoted sections 49 until it has traveled the full length of these sections that the lugs on the box will 115 not follow around between parallel curved bars and the allowance referred to must, therefore, be provided.

At points where the cables and tracks are expected to turn a corner special provisions must be made to prevent the cables jumping the grooved guide pulleys necessarily employed. In Figs. 9 and 10 I illustrate the special construction of the corners I have devised for this purpose. In a suitable skeleton frame-work 54 are journaled 120 grooved guide pulleys 9 and 10. These are set in different planes and overlap one another, as shown, so that the tracks and cables require to be spread as little as pos- 125 130

sible at the corner. Ordinarily the cables lie in the bottom of the brackets 2 below the tracks, but at the corners they must rise and pass above the tracks to engage the guide pulleys. I, therefore, offset the tracks, as shown in Fig. 10, adjacent the pulley so that the cable when lying in the bottom of the brackets midway between the rails is substantially tangential to the grooved rim 5 of the pulley. The cables have a tendency, therefore, to draw toward the inner supporting members of the bracket 55 adjacent the guide pulleys 9 and 10. I take advantage of this tendency to provide means for 10 catching and holding the cables in case a sudden slack in the cable causes a tendency for it to snap out of the groove in the adjacent guide pulley. The inner supporting lugs 56 for the rails on the bracket 55 are 15 therefore curved, as shown in Fig. 13, or otherwise dropped below the level of the rails to form in effect cable catchers which will receive the cables and hold them up in case of a sudden slackening occurring. The 20 pulleys occupy naturally some considerable amount of vertical space and the rails 1 of the tracks must, therefore, be somewhat more spread vertically at the corners than they are along the main portion of the line. 25 This is illustrated in Fig. 9, and the brackets 2 adjacent the corners of brackets 55 are shaped accordingly. The rails adjacent the guide pulleys are concentric with parts of the guide pulleys and are substantially on a level with the lower flanges 30 of the grooves and close thereto so as to form a pocket which will receive and hold the cable in case a sudden slackening tends to cause it to fly out of the groove in the 35 pulley. To further increase the safety in this respect the side of the rail adjacent the pulley is preferably flattened, as shown particularly in Fig. 11, making it more difficult for the cable to ride over the track and fall 40 down. This arrangement of the inner rails of the tracks relative to the grooves in the pulleys, combined with the arrangement of the cable catchers on the brackets 55, and the offsetting of the tracks as described, 45 give a tangential lead to the cables to make it practically impossible for slackness of the cable to cause it to jump the guide pulleys. It will be noted that the portion of each inner track next the pulley and which 50 is tangential to the pulley rim is of an appreciable length and that the offset occurs 55 between the end of this tangential portion and the main track so that the cable, when no car is passing crosses above the rail before the tangential portion is reached and 60 therefore near the lower level of the rail.

What I claim as my invention is:—

1. In a cable carrier system the combination with a horizontal grooved guide pulley; of a track rail concentric with an arc 65

of the pulley, the side of the rail next the pulley being flattened and extending above the lower flange of the groove of the pulley in close proximity thereto.

2. In a cable carrier system the combination with a horizontal grooved guide pulley; of a track rail concentric with an arc of the pulley, the rail extending above the lower flange of the groove of the pulley and spaced therefrom a distance less than the diameter 70 of the cable employed so as to form a cable catching pocket.

3. In a cable carrier system using a two rail track, the combination with a horizontal grooved guide pulley; of the inner track rail concentric with an arc of the pulley, the rail extending above the lower flange 80 of the groove of the pulley and spaced therefrom a distance less than the diameter of the cable employed so as to form a cable 85 catching pocket.

4. In a cable carrier system, the combination with a horizontal grooved guide pulley; of a track rail concentric with an arc of the pulley, the rail extending above the lower flange of the groove of the pulley and spaced therefrom a distance less than the diameter 90 of the cable employed; a box adapted to run on said rail; a cable passing around said pulley and normally lying in 95 the groove therein; and a cable grip on the box above its track engaging parts adapted to grip said cable.

5. In a cable carrier system using double tracks side by side the combination with a horizontal grooved guide pulley, of an inclined track rail rising from a lower level 100 to the level of the lower flange of the pulley; a supporting bracket for the track rail intermediate the ends of the inclined portion; having a laterally extending arm to which the rail is secured, said arm being depressed below the rail to form a cable 105 catcher.

6. In a cable carrier system using double tracks side by side the combination with a horizontal grooved guide pulley of a two rail track having the center line between the rails substantially tangential to the groove 110 in the pulley at one side, the said track adjacent the pulley being offset to bring the inner rail of the track into a position substantially tangential to the pulley flanges, the track rails rising from a lower level substantially to the level of the lower flange of 115 the pulley.

7. In a cable carrier system the combination of a pair of horizontal track rails having a gap formed therein; a vertically swinging frame; a short track section carried by the frame normally fitting the gap; and a second track section carried by the frame adapted when the frame is swung 125 up to fit in the gap.

8. In a cable carrier system the combina- 130

- tion of a pair of horizontal track rails having a gap formed therein; a vertically swinging frame; a short track section carried by the frame normally fitting the 5 gap; a second track section carried by the frame adapted when the frame is swung up to fit in the gap; a box adapted to be pushed onto the second track section when the frame is down; cable grip 10 mechanism carried by the box; and means carried by the swinging frame for opening the grip mechanism as a box is fitted in place, said opening means being adapted to release the grip mechanism when the box 15 is pushed forward off said track section.
9. In a cable carrier system the combination of a pair of horizontal track rails having a gap formed therein; a vertically swinging frame; a short track section carried 20 by the frame normally fitting the gap; a second track section carried by the frame adapted when the frame is swung up to fit in the gap; a box adapted to be pushed onto the second track section when the frame 25 is down; cable grip mechanism carried by the box; and means carried by the swinging frame for opening the grip mechanism as a box is fitted in place, said opening means being adapted to release the grip mechanism 30 when the box is pushed forward off said track section; and automatic means for pushing forward said box as the swinging frame is raised.
10. In a cable carrier system the combination 35 of a pair of horizontal track rails having a gap formed therein; a vertically swinging frame; a short track section carried by the frame normally fitting the gap; a second track section carried by the frame adapted when the frame is swung up to fit in the gap; a box adapted to be pushed onto the second track section when the frame is down; cable grip mechanism carried by the box; and means carried by the swinging 40 frame for opening the grip mechanism as a box is fitted in place, said opening means being adapted to release the grip mechanism when the box is pushed forward off said track section; a cam lever pivoted on a stationary part adapted to engage the rear 45 end of the box when the swinging frame is swung up; and a finger on the cam lever adapted to be engaged by the top of the box to cause the operation of the cam lever.
- 55 11. In a cable carrier system the combination of a pair of horizontal track rails having a permanent gap formed in each; boxes having projecting lugs at opposite sides in different predetermined positions; 60 parallel bars at different levels below each rail spanning the gap adapted to engage the lugs of certain of the boxes to carry them over the gap; and a pair of bars below each rail leading down to a lower level and adapted 65 to receive the lugs of one of said boxes

between them; a track at a lower level adapted to receive said box; cable grip mechanism carried by the said box; and means adjacent the lower track to engage and release said cable grip mechanism. 70

12. In a cable carrier system the combination of a pair of horizontal track rails having a permanent gap formed in each; boxes having projecting lugs at opposite sides in different predetermined positions; 75 parallel bars at different levels below each rail spanning the gap adapted to engage the lugs of certain of the boxes to carry them over the gap; and a pair of bars below each rail leading down to a lower level 80 and adapted to receive the lugs of one of said boxes between them; cable grip mechanism carried by said box and means adjacent the lower ends of the said pair of bars adapted to engage and release the cable 85 grip mechanism.

13. In a cable carrier system the combination of a pair of horizontal track rails having a gap formed in each; vertical supports below each rail; thin straight bars carried by the supports parallel to the rails, the said supports being adapted to removably receive the bars at different levels; two pair of thin bent bars curved downwardly, one bar of each pair branching from one of the straight bars near one end thereof and the other bar of each pair removably connected to one of said supports at one of its bar receiving positions; and a pair of supports at a lower level to which the lower 90 ends of the two pairs of bent bars are removably connected, the said pair of supports being adapted to receive said ends in any one of a plurality of positions. 95

14. In a cable carrier system the combination of a box; a plunger at one end movable vertically in suitable guides; a pair of pivoted jaws adapted to be swung downwardly by said plunger to grip or release a cable, said jaws being pivoted at each side 100 of and in substantial alinement with the position of the cable; a spring tending to move the parts to their cable gripping position, with the gripping parts in substantial alinement with the pivots, said plunger projecting below the bottom of the box; a track 105 on which said box is adapted to run and plunger engaging means carried adjacent the track adapted to engage the plunger and force it up to its cable releasing position as the box passes. 115

15. In a cable carrier system the combination of a box; a plunger at one end movable vertically in suitable guides; a yoke at the upper end of the plunger; a pair of pivoted jaws adapted to swing down to grip a cable between them; a pin and slot connection between the yoke and jaws; and a spring engaging the plunger and a stationary part tending to move the plunger to 125 130

cause the jaws to assume their cable gripping position; the yoke being adapted to serve as a cable support as the jaws open or close.

- 5 16. In a cable carrier system using double tracks side by side the combination with a horizontal guide pulley of a rail offset adjacent the pulley to present, in plan, a portion of some length adjacent the pulley substantially tangential to the groove in the pulley, the rail adjacent the pulley rising gradually from a lower level substantially to the level of the lower flange of the pulley.
- 10 17. In a cable carrier system using double tracks side by side the combination with a horizontal guide pulley of a rail offset adjacent the pulley to present, in plan, a portion of some length adjacent the pulley, substantially tangential to the groove in the pulley, the rail adjacent the pulley rising gradually from a lower level substantially to the level of the lower flange of the pulley.
- 15 18. In a cable carrier system using double tracks side by side the combination with a horizontal guide pulley of a rail offset adjacent the pulley to present, in plan, a portion of some length adjacent the pulley, substantially tangential to the groove in the pulley, the rail adjacent the pulley rising gradually from a lower level substantially to the level of the lower flange of the pulley.
- 20 19. In a cable carrier system using double tracks side by side the combination with a horizontal guide pulley of a rail offset adjacent the pulley to present, in plan, a portion of some length adjacent the pulley, substantially tangential to the groove in the pulley, the rail adjacent the pulley rising gradually from a lower level substantially to the level of the lower flange of the pulley

the offset being located adjacent the lower rail level.

- 25 20. In a cable carrier system using double tracks side by side the combination with a horizontal guide pulley of a rail offset adjacent the pulley to present, in plan, a portion of some length adjacent the pulley substantially tangential to the groove in the pulley, the rail adjacent the pulley rising gradually from a lower level substantially to the level of the lower flange of the pulley the offset being located adjacent the lower rail level, and a cable catcher located adjacent the pulley side of the rail at the tangential part thereof.
- 30 21. In a cable carrier system using double tracks side by side the combination with a horizontal guide pulley of a rail offset adjacent the pulley to present, in plan, a portion of some length adjacent the pulley substantially tangential to the groove in the pulley, the rail adjacent the pulley rising gradually from a lower level substantially to the level of the lower flange of the pulley the offset being located adjacent the lower rail level, and a cable catcher located adjacent the pulley side of the rail at the tangential part thereof.
- 35 22. In a cable carrier system using double tracks side by side the combination with a horizontal guide pulley of a rail offset adjacent the pulley to present, in plan, a portion of some length adjacent the pulley substantially tangential to the groove in the pulley, the rail adjacent the pulley rising gradually from a lower level substantially to the level of the lower flange of the pulley the offset being located adjacent the lower rail level, and a cable catcher located adjacent the pulley side of the rail at the tangential part thereof.

Toronto, Ont., this 19th day of April, 1912.

FREDERICK J. H. HAZARD.
